UNITED STATES PATENT OFFICE.

ERNEST KIMMICH, OF DETROIT, MICHIGAN.

FIRE-POT ATTACHMENT.

1,225,440.

Specification of Letters Patent.

Patented May 8, 1917.

Application filed November 10, 1916. Serial No. 180,534.

To all whom it may concern:

Be it known that I, ERNEST KIMMICH, a citizen of the United States of America, residing at Detroit, in the county of Wayne 5 and State of Michigan, have invented certain new and useful Improvements in Fire-Pot Attachments, of which the following is a specification, reference being had therein to the accompanying drawings.

10 It is the object of the invention to provide a simple attachment for furnaces by which the size of the fire-pot may be reduced to lessen the fuel consumption in moderate weather. It is a further object to obtain a 15 construction which will not interfere with the ordinary manipulation of the furnace and which will not become excessively heated so as to burn out. With these objects in view, the invention comprises the 20 novel construction as hereinafter set forth.

In the drawings:

Figure 1 is a vertical central section through the fire-pot of a furnace, showing my improvement applied thereto;

25 Fig. 2 is a similar section in a plane at right angles to Fig. 1.

A is the fire-pot of an ordinary furnace and B are the grate bars arranged below said fire-pot and provided with a common 30 shaking mechanism, such as the rock-arms C and connecting bar D. E is the furnace dome.

35 My attachment comprises a vertical division plate F, which extends in a central plane transversely of the fire-pot, and a cooperating horizontal plate G, which closes the space on one side of the division plate. The plate F is suspended within the pot, preferably by lugs H at the opposite ends 40 thereof, which engage the usual shoulder I on the fire-pot. The plate is also held in position by the tapering form of the fire-pot and by the fact that it is placed diametrically thereacross and therefore is too long 45 to be displaced laterally. The lower edge of the plate F is also sufficiently above the grate bars B to permit the free rocking of the latter without interference. The plate G is supported by a shoulder J upon the 50 plate F and also by the ledge I of the fire-pot. The plate F overlaps the inner edge of the plate G, as indicated at K, thereby preventing the latter plate from becoming displaced.

55 In use, whenever it is desired to restrict the size of the fire-pot the plates F and G,

which are of a size for insertion through the fire-door of the furnace, may be readily introduced into the fire-pot, the plate F being first positioned and the plate G then 60 dropped into engagement therewith. When in place fuel is introduced into the uncovered compartment of the pot and the fire started. The plate G by closing the top of the empty portion of the pot prevents short 65 circuiting of the air which would check the fire, and at the same time, the space below this plate and at one side of the plate F is in free air communication with the ash-pit. Thus when the contact of the hot fuel with 70 the plate F causes it to rise in temperature a circulation of air will be established, the hot air rising adjacent to said plate and descending along the cooled outer wall of the fire pot and through the open grate spaces 75 into the ash-pit. Here it will displace the cooler air from the ash-pit which will rise against the plate F and dissipate the heat thereof.

At any time when the full furnace capacity is required, the plates F and G can 80 be readily removed and without the necessity of drawing the fire. This removal may be facilitated by the arrangement of a hook L centrally of the furnace dome, with which 85 a pulley and line may be engaged to assist in lifting said plates.

What I claim as my invention is:

1. The combination with a fire-pot and a series of movable grate-bars arranged therebeneath and coacting therewith, of a division plate for the fire-pot extending across the same and suspended to clear said grate-bars and permit shaking movement thereof, and a horizontal plate at the top of said division 90 plate for excluding fuel from one side of the latter and preventing short circuiting of the air, the space beneath said horizontal plate at one side of said division plate being in free air communication with the space below 95 the grate to permit circulation of the air and cooling of said plates.

2. The combination with a fire-pot and a series of movable grate-bars arranged therebeneath and coacting therewith, of a vertical 105 division plate extending diametrically across said fire-pot and suspended therein, with its lower edge clearing the grate bars, and a horizontal plate for closing the space at one side of said division plate and at the upper 110 end thereof, said horizontal plate being supported on said division plate and abutting

thereagainst to prevent lateral displacement, the space beneath said horizontal plate being in free air communication with the space below the grate.

- 5 3. The combination with a tapering fire-pot having an interior ledge and a series of movable grate bars arranged below said fire-pot and coacting therewith, of a division plate arranged in a vertical plane to extend
10 diametrically across said fire-pot and conforming to the taper thereof, said plate having a ledge substantially on a level with that of the fire-pot, the lower edge of said division plate clearing said grate bars and its
15 upper edge portion being supported at its ends upon said ledge of the fire-pot and a horizontal plate resting upon said ledges of the vertical plate and fire-pot and closing the space at one side of the vertical plate.

4. The combination with a fire-pot having an interior ledge and a series of movable grate bars arranged therebeneath and coacting therewith, of a vertical division plate extending across said fire-pot and suspended therein with its lower edge clearing the grate 25 bars, said plate being restrained against lateral displacement by the fire-pot wall and having a ledge substantially opposite that upon the fire-pot wall, and a horizontal plate supported on said ledges and restrained 30 against lateral displacement by the vertical plate, a space having free air communication with the space below the grate, being formed between the grate and said horizontal plate.

35 In testimony whereof I affix my signature.

ERNEST KIMMICH.
